UNITED STATES PATENT OFFICE.

CHAMBERS E. GLENN, OF TERRA ALTA, WEST VIRGINIA.

SAFETY-CRANK FOR AUTOMOBILES.

1,233,773.

Specification of Letters Patent. Patented July 17, 1917.

Application filed April 1, 1916. Serial No. 88,385.

To all whom it may concern:

Be it known that I, CHAMBERS E. GLENN, a citizen of the United States, residing at Terra Alta, in the county of Preston and

5 State of West Virginia, have invented certain new and useful Improvements in Safety-Cranks for Automobiles, of which the following is a specification, reference being had to the accompanying drawings.

10 This invention is a safety crank designed more particularly to be used upon engines mounted on a vehicle.

One object of the invention is to provide means whereby the danger of a handle reversing when the engine back-fires, will be eliminated.

Another object of the invention is to provide means whereby the handle will be securely held against rotation in one direction.

20 A practical form of the invention is shown in the accompanying drawings, in which—

Figure 1 is a longitudinal section;

25 Fig. 2 is a front elevation;

Fig. 3 is a side elevation of a ratchet wheel showing the shaft and the sleeve and the key.

The shaft in this invention is made in two 30 separable sections comprising a front section 4 provided at one end with a left-handed threaded stem 5 coöperating with the other section 6. This section 6 is provided with a socket having corresponding threads.

35 The outer end of section 4 is provided with a stem 10 which has right-hand screw threads. The outer end portion of this stem carries no threads and is preferably square to engage with a square socket in the 40 starting handle 14. A nut 11 is provided for the stem 10.

The shaft section 4 has cut therein a keyway 8 which extends in a longitudinal direction over the major portion of the section. Surrounding this section 4 is a sleeve or quill having a corresponding key-way or slot through which a key 13 may be inserted to engage with the slot 8.

50 Slidable on this sleeve or quill 9 is a ratchet wheel 12 in which is cut a slot to correspond with the key 13. This ratchet wheel is adapted to have rotary movement in one direction only but is slidable the full length of the slot 8 and to prevent this 55 ratchet wheel 12 from rotating in an undesired direction, a pawl 16 engages with the

teeth of the ratchet wheel and to maintain this pawl in engagement with these teeth, a resilient member or spring 17 is provided. This pawl and this spring may be attached 60 to the vehicle in any convenient manner by suitable means.

In order to impart a rotary movement to the engine shaft and to disconnect itself when operating at its normal speed in the 65 desired direction, as after starting the engine, suitable means may be provided. This means may consist of ratchet teeth 18 in the section 6 to engage with suitable teeth 19 formed on the end or circumference of the 70 engine shaft.

To assemble this device, the two sections of the shaft are screwed together, then the sleeve 9 is put on the front section until it abuts against the shoulder of the rear section. Then the jam nut is set up tight 75 against the sleeve 9. The inner end of this sleeve forms a shoulder it will be seen which prevents the shaft section 6 from becoming jammed or screwing up too tightly on the 80 screw threads 5. When the shaft section 4 is screwed into the shaft section 6, then the inner end of the sleeve bears squarely against the outer end of the section 6. The

jam nut 11 is then set up tight against the 85 other end of the sleeve 9, thus securing a frictional engagement between both ends of the sleeve 9 and the shaft section 6 and jam nut 11. This permits such a secure engagement between the shaft section 4 and the 90

shaft section 6 that the shaft sections 4 and 6 will rotate together upon a rotation of the handle 14 in a direction to crank the engine but if the engine reverses, the shaft section 6 immediately unscrews from the shaft sec- 95

tion 4 and positively forces the shaft section 4 outward through the sleeve, the shaft section 6 remaining in engagement with the crank shaft of the engine. It will be noted that the detachment between the shaft sec- 100

tion 6 and the section 4 is immediate upon a reversal of the engine and this is of great importance as in many devices of this character there is not an immediate disengagement but the crank handle is not disengaged 105 from the crank shaft of the engine until the cranking device has been shifted outward far enough to disengage the teeth of the crank device from the teeth of the engine shaft. While this takes only a very 110

short period of time, yet it is sufficient to administer a severe blow to the operator,

With my device, however, the reversing of the engine immediately shifts the shaft 4 outward and there is an immediate disengagement between the section 6, which may 5 be under these circumstances assumed to be part of the crank shaft itself, and the section 14.

What is claimed is:—

1. Means for cranking internal combustion engines comprising a shaft section screw-threaded at one end, a member having screw-threaded engagement with the shaft section and having inclined clutch teeth on its extremity, the teeth being inclined in a direction reverse to the direction of the screw threads, a crank on the shaft section, and means for preventing the rotation of the shaft section in a direction reverse to the direction of effective driving rotation of said member. 10
2. In a device of the class described, the combination with a handle, of a plurality of shaft sections, one of said sections being provided with threaded stems, another of said sections being provided with a socket adapted to engage with one of said stems, a sleeve surrounding one of said sections, a ratchet wheel slideable on said sleeve, and means coöperating with the ratchet wheel 15 to limit the movement of said wheel in one direction. 20
3. In a device of the character described, the combination with a handle, of a plurality of shaft sections adapted to be connected together by screw means, one of said sections being provided with a key-way and key therein, a slotted sleeve surrounding said section, a ratchet wheel provided with a key-way slideable on said sleeve, means to prevent rotary movement of said latter 25 shaft section and the ratchet wheel in one direction, another of said sections adapted to coöperate with an engine shaft, the two sections adapted to rotate said engine shaft 30 in one direction by said handle. 35
4. A device of the character described comprising two separable shaft sections having screw-threaded engagement with each other, one of said sections having clutch 40 teeth adapted to engage with the clutch teeth on an engine shaft, the other of said sections being provided with a longitudinal key-way, a sleeve surrounding said section and formed with a longitudinally extending slot, a ratchet wheel mounted upon said 45 sleeve, a key engaging the ratchet wheel with the sleeve and with the slot of the shaft section, a nut having screw-threaded

engagement with the outer end of the shaft section and holding said sleeve in place, and 60 a crank mounted on the shaft section exterior to the nut. 65

5. Means for cranking internal combustion engines including two alining shaft sections having screw-threaded engagement 70 with each other whereby to secure relative unitary rotative movement upon a rotation in one direction, a crank handle upon one of the sections, and means preventing the reverse rotation of the last named section when the other section is reversely rotated but permitting longitudinal movement thereof whereby the last named section will unscrew from the other section upon said reverse rotation. 75

6. Means for cranking internal combustion engines including two alining shaft sections, one of said shaft sections having a reduced screw-threaded portion, the other shaft section having a bore internally screw 80 threaded to receive said reduced portion, said screw threaded engagement of the two shaft sections permitting unitary rotative movement of the sections upon a rotation in one direction, a crank handle mounted upon 85 the section having the reduced screw threaded portion, and means preventing reverse rotation of the last named section when the other section is rotated, but permitting outward movement thereof whereby one section will unscrew from the other section 90 upon said reverse rotation. 95

7. Means for cranking internal combustion engines including manually operable means for transmitting rotation to the engine shaft, said means consisting of two members having screw threaded engagement 100 with each other, there being a shoulder on one of said members limiting the longitudinal movement of the members relative to each other in one direction, said shoulder when it abuts against the other member causing a unitary rotation of both members in one direction, the shoulder permitting an independent rotation of the members in relatively opposite directions, said movement in opposite directions causing a relative longitudinal axial movement of the members, and means for preventing the reverse rotation of that member having said shoulder. 105 110

In testimony whereof I hereunto affix my signature in the presence of two witnesses.

CHAMBERS E. GLENN.
